Mississauga, Ontario, Canada

Filed Apr. 11, 1975, Ser. No. 567,270

Term of patent 14 years

Int. Cl. D26—05

U.S. Cl. D48—16 A

FIG. 1 is a fragmentary perspective view of a light diffuser showing my new design;

FIG. 2 is an inverted fragmentary perspective view thereof;

FIG. 3 is a fragmentary side elevational view thereof on an enlarged scale; and

FIG. 4 is an end elevational view thereof on an enlarged scale.

The light diffuser is broken away in FIGS. 1, 2 and 3 to indicate indeterminate length.

I claim:

The ornamental design for a light diffuser, as shown and described.
